DISPOSABLE INSERT FOR A TRAY

Robert K. Parish, 3628 Dresher Road,
Cornwells Heights, Pa. 19020

Filed Oct. 20, 1966, Ser. No. 4,358

Term of patent 14 years

(Cl. D44—10)

FIG. 1 is a perspective view of a disposable insert for a tray showing my new design in exploded relationship with a tray in broken lines for illustrative purposes;

FIG. 2 is a reduced scale front elevational view;

FIG. 3 is a rear elevational view thereof;

FIG. 4 is a bottom plan view thereof;

FIG. 5 is a right side elevational view; and

FIG. 6 is a left side elevational view.

I claim:

The ornamental design for a disposable insert for a tray, substantially as shown and described.
